UNITED STATES PATENT OFFICE.

OLIVER P. GREENSTREET, OF OWENSVILLE, MISSOURI, ASSIGNOR OF ONE-HALF TO
JOSEPH T. TATE, OF OWENSVILLE, MISSOURI.

METALLIC SHINGLE.

Application filed December 1, 1925. Serial No. 72,530.

This invention relates to metallic roofing shingles, and the general object of the invention is to improve upon the shingle illustrated in my Patent No. 1,432,999, granted 5 October 24, 1922, and particularly to so construct the shingle that any water getting into the lock between one shingle and the next adjacent lateral shingle will not run over the edge of the lock, causing leakage, 10 but will run out or down onto the shingle immediately below and so down to the exterior of the roof.

A further object is to provide interlocking flanges on the lateral margins of the 15 shingles which will permit the shingles to be readily engaged with each other and which, when interlocked, will provide rain-proof joints between the shingles, and further to so construct the shingle as to prevent 20 the entrance of water at the lower ends of the beads.

My invention is illustrated in the accompanying drawing, wherein:—

Figure 1 is a fragmentary top plan view 25 of a series of shingles constructed in accordance with my invention and applied to a roof;

Figure 2 is a section on the line 2—2 of Fig. 1;

Figure 3 is a like section to Figure 2 but showing the adjacent margins of the two plates separated;

Figure 4 is a section on the line 4—4 of Fig. 1;

Figure 5 is a like view to Figure 4 but showing the two parts separated;

Figure 6 is a fragmentary perspective view of the lower corners of two adjacent shingles, the shingles being separated;

Referring to the drawing, it will be seen 40 that each shingle consists of a sheet of metal 10 which is preferably of zinc, though it might be made of any other desirable metal and of any suitable gauge, each 45 shingle being formed with a side flange, as will be later described. These side flanges terminate short of the upper end of the shingle and this upper end of the shingle is 50 bent downward upon itself, as at 11, below the top of the shingle, then again bent upon itself and extended upward above the top of the shingle, as at 12, this attaching flange so formed being perforated for the passage 55 of attaching nails, as at 13. The lower edge of the shingle is formed with a flange which

extends downward, as at 14, and then inward, as at 15, this flange on one side terminating short of the corresponding lateral bead, as at 16, and on the other side being cut away as at 17. One side margin of the metal sheet forming the shingle is bent inward between the body of the shingle, as at 18, and then is bent downward and upward to form a trough 19, the upper edge of this trough extending above the upper face of the shingle. The opposite side margin of the shingle is bent upward to form an upwardly convex bead 20 and then extended laterally to form a flat flange 21 on the same level as the body of the shingle.

As before remarked, the flange 14 terminates short of the bend 18, as illustrated in Figure 6, but this flange 14 and the portion 15 are extended beyond the other side edge of the shingle, as at 17.

It will be understood that the shingles are laid as illustrated in Figure 1, with the bead 20 extending upward and the gutter or trough 19 downward, the flanges 12 being nailed to the roof sheathing. After one course of shingles has been laid, an upper course is laid by engaging the inturned flanges 15 with the portions 11 in the manner illustrated in Figure 4, so that the nails of the course below are entirely covered by the shingle above. Of course, the upper row of shingles is laid to break joint with the lower row in the usual manner.

The lateral margins of the same course of shingles are interlocked with each other, as 90 illustrated in Figure 2, that is, the flat marginal portion 21 is inserted beneath the outstanding bend 18 and over the trough 19 and then the shingle which is so inserted is turned down into a position against the 95 roof or sheathing and forced laterally inward until the edge of one shingle bears against the under face of the bead 20 of the other shingle. Under these circumstances a trough or gutter 19 is provided which extends down 100 the entire length of the shingle and is disposed between two shingles, while the outer wall of the trough 19 extends slightly above the level of the shingle itself and bears tightly against the under face of the bead 105 20 of the next adjacent shingle.

Inasmuch as the flange 14 is cut away at 16, and 17, it follows that any water which may collect in this trough will run downward and be discharged onto the outer face 110

of the shingle below so that any water getting into the lock and more specifically into the gutter 19 will not run over the edge, causing leakage, but will run downward 5 in this gutter or trough onto the shingle below.

It will be seen from Figure 2 that the margin of the trough 19 extends upward into the bead 20 about a quarter of an inch 10 higher than the face of the shingle, thus preventing any chance of the water overflowing over this edge and thereby leaking. I have found in actual practice that this 15 practically does away with any leakage between the shingles even in violent storms where ordinarily water is liable to beat in, and that the roofing so formed is particularly effective.

I claim:—

20 1. A metallic shingle of the character described having on one lateral margin thereof an upwardly convex, longitudinally extending bead and a flat portion beyond the bead and the other margin thereof having 25 the metal of the shingle inwardly bent

beneath and parallel to the body of the shingle, then downwardly and laterally curved below the plane of the shingle and extending upward below the plane of the shingle to form an exterior wall, the exterior 30 wall of one shingle being adapted to fit within the bead of the other shingle.

2. A metallic shingle comprising a rectangular sheet of metal, one side margin of the sheet being formed to provide an upwardly convex, longitudinally extending bead, the opposite margin of the sheet being formed to provide a longitudinally extending, transversely concave trough depending below the lower face of the shingle and having an exterior wall extending above the level of the upper face of the shingle and adapted to extend into the bead of the next 40 adjacent shingle, the trough constituting a longitudinally extending gutter conveying 45 water upon the face of the shingle next below.

In testimony whereof I hereunto affix my signature.

OLIVER P. GREENSTREET
